(57) **ABSTRACT**

An auxiliary caliber weapon system that allows a conventional shotgun, such as a pump action shotgun or other firearm, including artillery weapons to be modified to fire ammunition rounds of a selectable caliber. The system includes a barrel assembly and to load an ammunition round within the shotgun or other firearm and a shotgun shell adapter of a selected auxiliary caliber is utilized. The shotgun includes a stock with grip a receiver and an internal magazine. The shotgun barrel is removed and the system's barrel assembly is attached to the shotgun, interfacing with the receiver. An ammunition round of a selected auxiliary caliber is inserted into the adapter, which is then placed into the magazine via a loading port. When the shotgun pump is actuated the adapter with the auxiliary caliber round is loaded from the magazine into the receiver, and is ready to be fired. After being fired, the pump is actuated again causing the adapter to be ejected out an ejection port and another adapter with an auxiliary caliber round to be loaded. For use with an artillery weapon, the adapter is scaled to a larger dimension to accommodate the larger size ammunition used but the functionality is the same.

AUXILIARY CALIBER WEAPON SYSTEM

TECHNICAL FIELD

The invention generally pertains to firearms, guns and artillery, and more particularly to a system that allows a conventional weapon to be quickly and easily modified to fire ammunition that can be used as an auxiliary selected caliber for target practice training or other purposes.

BACKGROUND ART

There are many various firearms used throughout the world for a variety of purposes including military, home/personal defense, hunting, sport/target shooting, or collecting. There are multiple types of guns or firearms: handguns, rifles, shotguns and artillery weapons including cannons. Although all of these firearms can each be utilized for multiple purposes, there are specific purposes for which a particular type of gun might be especially well-suited. For example, bird hunting (or skeet shooting) typically requires the use of a shotgun, when carrying (or wearing) a gun for personal protection a handgun is preferred, and military training often requires the use of the artillery weapons.

Other than the type of firearm, a main method of differentiating firearms is by the caliber of the ammunition (or bullet) that the firearm uses or, in the case of a shotgun, the gauge of the shell. For both rifles and handguns, the calibers can typically range from 0.22 to 0.50, with metric sizes also sometimes used. The caliber indicates the diameter of the bullet, or in some metric sizes both the diameter and length. Usually, the main difference between handgun, rifle and artillery ammunition is the actual size of the shell (which is the bullet and cartridge case that maintains the primer and gunpowder). Handgun ammunition is typically smaller than rifle ammunition, which allows the rifle cartridge to use a larger amount of gunpowder, resulting in the rifle having greater velocity and more power when fired. The longer barrels used for rifles also results in greater velocity and more power compared to handguns. This also applies to artillery weapons which have much larger and longer barrels that allow a round to be fired with great power a long distance.

Having many choices when deciding which particular type of firearm and caliber is generally a benefit. There are problems though. One major problem is that when a person does require multiple guns with different calibers. The most common solution is to acquire however many guns/calibers are necessary. This can be expensive and when the guns are not in use they must be safely stored. This problem is exacerbated when a person is away from their residence, such as when they are on a camping and hunting trip. In this scenario, when multiple guns are necessary, the person has no choice but to bring multiple guns with them. This is very inconvenient if not difficult, the guns must be carried to a camping or hunting site, and the guns must be kept in a safe location, not exposed to the elements. Another issue is that when target shooting, usually a large number of bullets are fired. Ammunition can be expensive, and the cost adds up quickly as bullets are repeatedly fired during target shooting. Many target shooters will bring larger caliber guns along with small caliber such as a .22 or .22LR. But again, this necessitates the bringing of multiple guns to the location where the target shooting is occurring.

For artillery weapons such as a cannon, the ammunition is much more expensive, and during training a large amount of ammunition is required which results in a high cost.

Training must be performed and the only way for soldiers to become accustomed to and proficient with a cannon is to use the actual weapon.

The inventive system addresses and solves these problems by providing the ability to modify a conventional firearms or artillery weapon such as a cannon to fire ammunition other than the standard respective ammunition. For a shotgun, the system's solution is to provide interchangeable barrels, each sized to fire a selected caliber and that can be quickly and easily attached to a shotgun, along with a adapter that has the same size as a shotgun shell and therefore can be loaded into a shotgun magazine or inserted into a shotgun breach, fired, and ejected. For, an artillery weapon such as a cannon, the adapter is scaled up to a larger size that fits within the cannon. The only difference between the use for a shotgun or an artillery weapon is the size of the adapter, the functionality is the same.

A search of the prior art did not disclose any literature or patents that read directly on the claims of the instant invention. However, the following U.S. patents are considered related:

PAT. NO.	INVENTOR	ISSUED
2,059,658 2,321,737	Sandine Engel	Nov. 3, 1936 Jun. 15, 1943

The U.S. Pat. No. 2,059,658 patent discloses a gauge reduction liner for incorporation with a shotgun of a given gauge to permit the use of smaller gauge ammunition. The invention utilizes a novel ejecting mechanism for shell of smaller gauge, constructed and arranged to be operated by the gun ejector for the larger gauge shells.

The U.S. Pat. No. 2,321,737 patent discloses a converter cartridge for use in high-powered rifle to adapt the chambers thereof for loading therein low-powered shorter cartridges. The cartridge for use particularly with bottleneck type, low-powered, center fire cartridge and equipped for easy and secure loading of the low-powered cartridge and for reloading repeatedly.

DISCLOSURE OF THE INVENTION

An auxiliary caliber weapon system that allows a conventional shotgun such as a pump action shotgun or other firearm, to fire a selected caliber round which is loaded via the shotgun's standard magazine. The system includes a barrel assembly having a hub sleeve bush, a shotgun barrel sleeve, an auxiliary caliber barrel shank and an auxiliary caliber barrel. Located at a distal end of the barrel is front sight with a front sight attachment member, and located adjacent the barrel's distal end is a take down mount, also with a take down mount attachment member.

To facilitate the use of other, auxiliary rounds with the shotgun, an adapter is utilized. The adapter is dimensioned exactly the same as the size of the shotgun shell which is being converted. The adapter is preferably made of a thin metal or plastic and has an outer surface, an inner surface, and a head case face. Extending along and equidistantly positioned on the head case face and down the body of the adapter are preferably three slots. At the center of the head case face is an auxiliary caliber round inlet that allows a round to be inserted and maintained within the adapter. The inlet is dimensioned such that a round's first end, which has a standard extractor groove, is tightly placed with the inlet on an inlet groove and circularly extends into the round's extracted groove. The inlet expands during insertion of the round, and once the round is inserted and clicked in place, pressure contract that maintains the round in a substantially straight position within the adapter on center. The size of the adapter's inlet will vary, depending on the round caliber that is used.

In order to convert a shotgun to load and fire the auxiliary caliber round within the adapter, a person simply removes the stock shotgun barrel and replaces the barrel with the system's barrel assembly. It should be noted, that as with the adapter, the barrel assembly is designed to accept a particular auxiliary caliber round. By use of this system, instead of having or transporting multiple guns of various calibers, a person will only need to have a single shotgun, which can remain functional as a shotgun, and also have multiple barrel assemblies with the adapters. It is much easier to store or transport a single shotgun with multiple barrels than multiple guns of various calibers.

Once the barrel assembly has been attached to the shotgun, the adapter(s), with inserted selected caliber rounds are loaded into the shotgun's magazine. The number of adapters that can be loaded into the shotgun's magazine is the same number of standard shotgun shells that can be loaded. As the shotgun pump is actuated the adapter will be loaded and can be fired. Each subsequent pump action will eject the adapter with empty auxiliary caliber shell, and load another. This action can be repeated until the magazine is empty. If a person decides they need or desire a different caliber, the barrel assembly is simply replaced and the appropriate caliber adapters are loaded.

As an additional embodiment, an ACWS can be used to fire auxiliary caliber ammunition from a larger caliber artillery weapon. The functionality of using the adapter in a

larger caliber artillery weapon such as a cannon is the same as it is for a shotgun. The only difference is that the adapter is scaled up to fit the dimension of the cannon ammunition. The use of auxiliary caliber ammunition in an artillery cannon can provide significant benefits, especially in cost savings. During certain actions such as training, a large quantity of ammunition is used. By replacing the standard ammunition with auxiliary caliber ammunition a major cost saving can be achieved.

10 In view of the above disclosure, the primary object of the invention is to produce a an auxiliary caliber weapon system that utilizes a barrel assembly to allow a person to quickly and easily convert a conventional shotgun, other firearm or cannon to fire ammunition rounds of a selected caliber.

15 In addition to the primary object of the invention it is also an object of the invention to provide an auxiliary caliber weapon system that:

facilitates quick and easy conversion of a shotgun or other firearm,
20 is reliable and safe,
reduces the number of guns that must be stored or carried,
is especially useful for "preppers" and other survivalists,
reduces the cost of target shooting by allowing the use of
25 small caliber, low-cost ammunition
is cost effective from both a manufacturer's and consumer's point of view.

These and other objects and advantages of the present invention will become apparent from the subsequent detailed description of the preferred embodiment and the appended claims taken in conjunction with the accompanying drawings.

BRIEF DESCRIPTION OF THE DRAWINGS

35 FIG. 1 is an orthographic view of a an auxiliary caliber weapon system showing a barrel assembly and a shotgun shell adapter.

FIG. 2 is an orthographic rear view of the adapter.

FIG. 3 is an elevational rear view of the adapter.

40 FIG. 4 is an orthographic cut-away view of the adapter.
FIG. 5 is an elevational side view of the adapter with an ammunition round about to be inserted.

FIG. 6 is a cut-away view of the adapter with an ammunition round inserted.

45 FIG. 7 is an elevational side view of the conventional shotgun and a shotgun with the system's auxiliary caliber barrel.

FIG. 8 is an elevational side view of an artillery shell adapter.

50 FIG. 9 is an elevational cut-away view of the artillery adapter.

FIG. 10 is an elevational cut-away view of the artillery adapter with an auxiliary round inserted.

FIG. 11 is an elevational side view of a conventional artillery cannon, also known as a chain gun.

55 FIG. 12 is a side cut-a-way view of the barrel assembly

BEST MODE FOR CARRYING OUT THE INVENTION

60 The best mode for carrying out the invention is presented in terms that disclose a preferred embodiment with multiple design configurations of an an auxiliary caliber weapon system (ACWS). Firearms are available in a large variety of types, sizes and calibers. The three common categories of firearms include rifle, shotguns, a handguns, all of which can have multiple shapes and sizes, as well as the caliber of the

ammunition a firearm shoots. The type and caliber of a selected firearm depends on the requirement of use and preference of the person using the firearm. For ease of carrying or concealment, a handgun is typically preferred. For an activity such as animal hunting, a rifle is most commonly used, and for bird hunting or skeet shooting a shotgun is usually chosen.

If a person participates in multiple activities, they do not have a choice but to purchase, store and transport multiple type of firearms. It is not only expensive to purchase multiple firearms, but they must be safely stored when not in use, which often requires the ownership of a gun safe. Also, a major drawback is that when a person requires the use of multiple guns at a distant location such as on a hunting and camping trip, all of the guns must be carried to the location. The auxiliary caliber weapon system **10** provides a solution to these problems by allowing a conventional shotgun to be modified to fire other calibers of centerfire or rimfire ammunition. The system **10** utilizes a shotgun platform to which barrels of various caliber can be attached, as shown in FIG. 7. A person will then be able to selectively choose to fire the standard shotgun shell or any other caliber ammunition, while only needing to own and carry the shotgun and a barrel for each caliber. A specially designed shotgun shell adapter facilities the use of the interchangeable barrel on the shotgun.

The ACWS **10**, as shown in FIGS. 1-12, is essentially comprised of a barrel assembly **12** and a shotgun shell adapter **48**. The barrel assembly **12** is designed to be used with a specific manufacturer's shotgun, thereby possibly requiring modification to the barrel assembly **12** design. These modifications are anticipated and do not deviate from the scope of the inventive concept. The system **10** can effectively be adapted and utilized for use with any type of shotgun **70**, with the only requirement being the shotgun's use of a conventional shotgun.

As shown in FIGS. 1 and 12, the barrel assembly **12** is comprised of a hub sleeve bush **14** that functions as a receiver interface. A shotgun barrel sleeve **18** barrel connection section having a shotgun chamber **20** is integrally attached to and extends forward from the hub sleeve bush **14**. The shotgun chamber is located within an auxiliary caliber barrel shank **22**, which also includes an auxiliary caliber chamber **24**.

Extending forward from the shotgun barrel sleeve **18** is an auxiliary caliber barrel **26** having a rifled barrel bore **32** therethrough. Located at the barrel distal end is a front sight **36** that is secured by a front sight attachment member **38**. Located adjacent the barrel distal end is a take down mount **42** that is secured by a takedown mount attachment member **44**. Each auxiliary barrel acts as an attachment and converts a shotgun to a rifle. The auxiliary barrel replacements are made according to instructions in an existing shotgun factory manual and the barrel is longer than a shotgun's magazine **86**. The ACWS barrel assembly has two chambers, one inside the other, as shown in cut-a-way in FIG. 12. One of the chambers is the shotgun chamber **20** and the other is the auxiliary caliber rifled chamber **24**. Around the shotgun chamber **20** and auxiliary caliber barrel shank **22** is a space for the adapter **48** to be inserted. When the shotgun **70** is actuated, such as by pump action, the adapter **48** moves from the magazine **86** to the shotgun chamber **20**, exactly between the shotgun chamber **20** and auxiliary caliber barrel shank **22** and an auxiliary caliber ammunition round **90** moves to the auxiliary caliber chamber **24**. The barrel assembly is made specifically to correspond to the gauge of any conventional shotgun, and is designed to replace the

shotgun's original barrel, by fitting into the receiver of the shotgun. Similar barrel systems used for artillery or cannon have the same functionality, only the dimensions are different.

The second element of the ACWS **10** is the adapter **48** which is a single component, integrally constructed as one piece, with no mechanical function. As shown in FIGS. 1-6, the adapter **48** is comprised of an outer surface **52**, an inner surface **54** and a head case face **56** having an auxiliary caliber round inlet **58** with a groove **60** extending along an inner perimeter. Extending along and equidistantly positioned on the head case face **56** and down the body of the adapter **48** are preferably three slots **66**. The adapter **48** also has an open end **64** opposite the head case face. The adapter **48** is designed to resemble a shotgun round casing and functions as a three-section jaw action that grips the auxiliary caliber round by applying pressure. An auxiliary caliber round **90** is inserted into the adapter **48** through the auxiliary caliber round inlet **58** on the head case face **56**, as shown in FIGS. 5 and 6. The jaw side of adapter expands and contracts back to form, with assistance from the three slots **66**, when a round is inserted or extracted from the adapter. Once clicked into place, the auxiliary caliber round is securely held by the jaw action. The groove **60** on the auxiliary caliber round inlet **58** is designed to interface and circumvent the diameter of a round's extractor groove **98**. It should be noted that the inlet groove **60** is a mirror image of an auxiliary caliber round extractor groove **98**. Once the round is inserted, the auxiliary caliber round inlet **58** compresses and grasps the round along the perimeter of the extractor groove **98**, as shown in FIG. 6. There is enough force on the round to maintain the round in a straight, centered position within the adapter **48**. This is important because the adapter's inner surface interfaces **54** with the barrel shank **22**, and the round must be directed straight into the auxiliary caliber barrel chamber **24**. To extract an empty shell from the adapter **48** the most efficient method is to insert an object (even a person's finger) into the adapter and simply push the empty shell out of the open end **64**.

As previously disclosed, the ACWS **10** functions with a conventional shotgun **70**. As shown in FIG. 7, the shotgun **70** includes a stock with a grip **72**, and a receiver **74** having a trigger **76**, a bolt **78**, an ejection port **80**, an extractor **82** and a loading port **84**. Positioned within and connected to the receiver **74** is an internal magazine **86**. The shotgun **70** also has a barrel **88** which is quickly and easily removable.

The ammunition round **90** can either be a centerfire type or a rimfire type. The round **90** includes a cartridge case **92** with a first end **94** having a primer opening **96** and the previously disclosed extractor groove **98**, as shown in FIGS. 5 and 6. A second end **100** of the cartridge case has an opening **102** into which is inserted a bullet **106** with a first end **108** ad a typically pointed or rounded second end **110**.

The barrel assembly **12** is made of metal such as steel, and the adapter **48** is preferably made of a thin metal, plastic or a composite. The barrel assembly **12** is longer than the shotgun magazine, and the adapter is dimensioned the same as the shotgun shell of the shotgun that is modified.

To use the ACWS **10**, a person removes the standard shotgun barrel. The system's barrel assembly **12** is attached onto the shotgun, with the assembly **12** interfacing with the shotgun's receiver **74**. An auxiliary caliber ammunition round is inserted into the adapter **48** as previously disclosed. The adapter **48** with round is then placed into the magazine **86** via the loading port **84**. The shotgun pump is then actuated which loads the adapter **48** with an auxiliary caliber round into the chambers **20,24** from where it can be fired.

When the shotgun pump is again actuated, the now round-less adapter is ejected through the ejection port **80** and a new adapter with round is loaded from the magazine. This action can be repeated up to the number of adapters with rounds that are placed into the magazine.

In an alternate embodiment, the ACWS **10** can be utilized to fire an auxiliary caliber ammunition round from a larger caliber artillery weapon, such as a cannon, as shown in FIG. **11**. The ACWS is especially viable for this purpose since there is a significant cost for each ammunition round fired from a cannon. This problem is exacerbated when it is realized that during training of soldiers to use a cannon, a large number of ammunition rounds must be fired. There have been attempts to offer a solution to this problem, but there is no solution that utilizes the adapter **48** of the ACWS **10**.

A benefit of using the ACWS is that it is mainly a matter of scale of the ease adapter. The inventive concept of using the adapter to load and fire auxiliary caliber ammunition into a larger caliber cannon is essentially the same as for a shotgun. For use with a cannon, the adapter is designated as element **50** and the other element designators are the same as the adapter.

As shown in FIGS. **8-10**, the adapter **50** is correspondingly dimensioned to accept an auxiliary caliber ammunition round. For whichever type of cannon is used, the adapter **50** is specifically shaped, as shown in FIGS. **8-10**. This is important because a training crew learning to use/fire a cannon will become familiar with and be able to manipulate the adapter **50** and when necessary, easily be able to switch to the conventional ammunition. Also, the ACWS **10** can be used with artillery weapons such as a chain gun which ammunition is fed into via an ammunition belt that maintains a multiplicity of ammunition rounds in-line, ready for use. As long as the adapter **50** is similarly shaped and dimensioned as a large caliber ammunition round, the ACWS can be effectively utilized for an artillery weapon such as a cannon.

While the invention has been described in detail and pictorially shown in the accompanying drawings it is not to be limited to such details, since many changes and modification may be made to the invention without departing from the spirit and the scope thereof. Hence, it is described to cover any and all modifications and forms which may come within the language and scope of the claims.

The invention claimed is:

1. An auxiliary caliber weapon system (ACWS) comprising:

a barrel assembly including:

a hub sleeve bush configured as a shotgun receiver interface,

a shotgun barrel sleeve having a chamber, and attached to and extending from the hub sleeve bush,

a shotgun chamber,

an auxiliary caliber barrel shank configured adjacent to the shotgun chamber,

an auxiliary caliber chamber,

an auxiliary caliber barrel extending from the auxiliary caliber chamber and having a rifled bore therethrough,

a shotgun shell adapter having:

a head case face having an auxiliary caliber round inlet with a groove,

three slots configured longitudinally on the adapter, and extending on the head case face to the inlet, the three slots cause the inlet to enlarge when pressure is

applied on the slots, thereby facilitating the insertion of a round into the adapter via the inlet, an open end that allows a bullet to exit the adapter when fired and provides access to push on a fired shell for extraction of the shell from the adapter via the inlet, a shotgun including:

a receiver with an ejection port for ejecting a shell or misfired round, an extractor for extracting a shell or misfired round, and a loading port for loading a round,

an internal magazine, and a barrel that is removable to allow an ACWS barrel assembly to be attached onto and interface with the shotgun receiver, the barrel configured to receive an ammunition round of an auxiliary caliber into the adapter which is configured to be placed in the shotgun magazine, the shotgun magazine configured to be positioned within the shotgun receiver during use.

2. The auxiliary caliber weapon system of claim **1** wherein the barrel assembly is longer than the shotgun magazine.

3. The auxiliary caliber weapon system of claim **1** wherein the inlet groove is a mirror image of an ammunition round's extractor groove.

4. The auxiliary caliber weapon system of claim **1** wherein the barrel assembly is configured to interface with shotgun receivers of multiple makes and models of shotguns.

5. The auxiliary caliber weapon system of claim **1** wherein the barrel assembly further comprises a front sight with attachment means located adjacent an upper distal end of the barrel.

6. The auxiliary caliber weapon system of claim **1** wherein the barrel assembly further comprises a take down mount with attachment means located a lower distal end of the barrel.

7. The auxiliary caliber weapon system of claim **1** wherein the adapter comprises a material selected from the group consisting of metal, plastic and composite.

8. An auxiliary caliber weapon system (ACWS) comprising:

a barrel assembly comprising:

a hub sleeve bush configured as a shotgun receiver interface,

a shotgun barrel sleeve having a chamber, and attached to and extending from the hub sleeve bush,

a shotgun chamber,

an auxiliary caliber barrel shank configured adjacent to the shotgun chamber,

an auxiliary caliber chamber,

an auxiliary caliber barrel extending from the auxiliary caliber chamber, and having a rifled bore therethrough,

a front sight configured at a distal end of the barrel assembly and including a front sight attachment member,

a take down mount configured adjacent the front sight and including a take down mount attachment member,

an adapter with a particular shotgun shell size, the adapter having:

a first end,

a second end,

an outer surface,

an inner surface,

9

a head case face having an auxiliary round inlet with a groove,
 three slots that cause the inlet to enlarge when pressure is applied on the slots, thereby facilitating the insertion of a round into the adapter via the inlet,
 an open end that allows a bullet to exit the adapter when fired and provides access to press on a fired shell for extraction of the shell from the adapter via the inlet,
 a shotgun including:
 a rearward extending stock with a downward-extending grip,
 a receiver having:
 a trigger,
 a bolt positioned within the receiver,
 an ejection port for ejecting a shell or misfired round,
 an extractor for extracting shell or misfired round,
 a loading port for loading a round,
 an internal magazine and
 a barrel that is removable to allow an ACWS barrel assembly to be attached onto and interface with the shotgun receiver, an ammunition round of a selected caliber is inserted into the adapter, which is then placed via the loading port into the shotgun maga-

zine from where the adapter is loaded into the shotgun receiver, ready to be fired.

9. The auxiliary caliber weapon system of claim 8 wherein the barrel assembly is longer than the shotgun magazine.

10. The auxiliary caliber weapon system of claim 8 wherein the barrel assembly interfaces with shotgun receivers of multiple makes and models of shotguns.

11. The auxiliary caliber weapon system of claim 8 wherein the adapter is made of a material selected from the group consisting of metal, plastic and composite.

12. The auxiliary caliber weapon system of claim 8 wherein the adapter accepts centerfire ammunition.

13. The auxiliary caliber weapon system of claim 8 wherein the adapter accepts rimfire ammunition.

14. The auxiliary caliber weapon system of claim 8 wherein the ammunition round comprises an extractor groove.

15. The auxiliary caliber weapon system of claim 8 wherein the inlet groove is a mirror image of the ammunition round extractor groove.
